UNITED STATES PATENT OFFICE

2,577,929

SHUTTLE

Matthew Michael Taylor, Spondon, near Derby, England, assignor to Celanese Corporation of America, a corporation of Delaware

Original application August 19, 1947, Serial No. 769,400. Divided and this application January 13, 1949, Serial No. 70,753. In Great Britain August 30, 1946

3 Claims. (Cl. 139—207)

1

This application, which is a divisional of Serial No. 769,400, filed August 19, 1947, relates to shuttles, and is particularly concerned with shuttles for use in automatic looms in which, on exhaustion of a weft supply package in the shuttle of the loom, a fresh supply package is automatically inserted into the shuttle to displace the exhausted package.

Weft supply packages for use in automatic looms of this type (often known as "cop-changing looms") are generally wound on weft package supports comprising a tube or spindle on which the yarn is wound, terminating in a heavy butt having several circumferential metal rings inset therein, which serve to locate the package in relation to gripping means within the shuttle adapted to engage and grip the butt. The large numbers of these yarn package supports required to carry a reasonable stock of ready-wound weft yarn represent a very considerable capital expenditure which is idle in the interval (sometimes considerable) between the exhaustion of a weft package in the loom and the return of the re-wound package support to the loom again. In order to reduce this expenditure, detachable butts have been proposed, e. g. for use in connection with mule cops, and in connection with ordinary weft pirns which are wound on slightly tapered cardboard or pressed fibre tubes into the base of which the detachable butt is screwed. These devices are not required in nearly such great numbers as the pirns of yarn that need to be in stock at any moment, since they can be applied to the yarn packages immediately before the yarn packages are supplied to the loom and are ready for re-use immediately upon exhaustion of the yarn packages in the loom. The devices, however, cause a substantial expenditure of time when they are being applied to the pirn tubes and are somewhat uncertain in use, being apt to come loose in the shuttle during weaving.

It has now been found possible, in automatic looms of the cop-changing type to use in conjunction with a weft pirn wound on a pirn tube having a small projecting flange at the base thereof, a detachable butt provided with a plain spindle that is simply inserted into the bore of the tube, the correct positioning of the pirn tube with its flange in contact with the face of the detachable butt being ensured during the insertion of the weft tube and butt into the shuttle, and being maintained firmly during weaving, by means provided in the shuttle for that purpose.

According to the present invention, therefore, a shuttle for use in automatic looms of the cop-

2

changing type and adapted to carry weft yarn wound on a flanged pirn tube provided with a detachable butt, comprises gripping means for receiving and gripping a detachable butt, carrying a flanged pirn tube and forced therewith into the shuttle, guide means presenting sloping surfaces adapted to engage the flange of said pirn tube and urge said flange into engagement with the face of said butt, and holding means adapted to engage said flange in the shuttle and to hold it firmly in engagement with said face when said butt is gripped by said gripping means. Preferably, the means for guiding and the means for holding the flange in engagement with the face of the butt are in the form of spring means, adapted to hold the flange in contact with the face of the detachable butt by spring pressure. Alternatively or in addition, however, some resilience in the pressure between flange and butt 10 may be provided for by the inclusion of a spring washer beneath the flange when it is applied to the butt spindle. Where spring means are employed to constitute the guiding and holding means, they can conveniently be formed as extensions of a pair of strong springs extending parallel to the length of the shuttle, and serving as the means for gripping the butt within the shuttle, said extensions reaching from the ends of said gripping means, upwards, inwards, rearwards and downwards.

The shuttle according to the invention renders practicable the use of a very simple form of detachable butt having a plain spindle adapted to fit snugly inside the bore of the pirn tube, the snugness of the fit being relied on to keep the pirn tube and the butt in engagement with one another until the pirn enters the shuttle. The fitting of such a butt to the pirn tube can be performed very rapidly at the loom and involves substantially no loss of time.

By way of example, one form of shuttle in accordance with the invention will now be described in greater detail with reference to the accompanying drawings in which:

Figure 1 is a plan of a shuttle provided with spring means for locking a pirn tube to a detachable butt therein, and

Figure 2 is a side elevation of the operative 50 spring means of Figure 1.

The arrangement described in the drawings is suitable for use in conjunction with pirns wound on pirn tubes made principally of cardboard or compressed fibre, but provided at the base with a metal ferrule, slightly coned to conform to the

taper of the pирн tube and carrying an outwardly extending flange of about $\frac{1}{8}$ " to $\frac{1}{6}$ " wide.

In the arrangement shown in the drawings the pирн tube is indicated at 1 and has a flange 3. The detachable butt to which the pирн tube 1 is fitted is in the form of a cylindrical member 4 having three rings 5 of spring steel inserted in circumferential grooves extending round the surface of the cylinder 4. Extending from the upper face of the cylinder 4 is a central spindle 6 adapted to fit snugly inside the pирн tube 1. The fit of the spindle 6 inside the bore of the pирн tube is relied on to keep the pирн tube and the butt in engagement with one another until the pирн enters the shuttle 7.

The assembled pирн and detachable butt fit into the shuttle 7 as shown in Figure 1, the rings 5 being engaged by the two limbs 8 of a strong V-shaped spring 9 fitted in the shuttle, the inner faces of the spring being notched as at 10 to receive the rings 5 and locate the pирн and butt. The shuttle 7 is open, as is usual in cop-changing looms, both at the top and bottom so that the assembled weft package can be forced in from the top of the shuttle, displacing an exhausted weft package which is thereby forced out of the bottom of the shuttle.

Extending from each limb 8 is an auxiliary spring 11 for the purpose of engaging the flange 3 of the pирн tube and pressing it firmly against the face of the detachable butt 4. Each auxiliary spring 11, extending at first parallel to the length of the shuttle 7 for a short distance, then turns upwards and rearwards, and slightly inwards, through a semicircle which brings it close to the upper face of the shuttle. The spring 11 then turns obliquely downwards at 12 and then sharply downwards at 13. When a pирн, complete with detachable butt 4, is forced into the shuttle to displace an exhausted pирн, the flange 3 of the pирн tube is engaged by the auxiliary springs 11 and is firmly held against the face of the butt 4 by the portions 13 of the springs 11. If the flange 3 is not quite in contact with said face in the first instance, the portions 12 of the

auxiliary springs 11 engage the flange and guide it into contact.

Having described my invention, what I desire to secure by Letters Patent is:

- 5 1. A shuttle for use in an automatic loom of the cop-changing type and adapted to carry weft yarn wound on a flanged pирн tube provided with a detachable butt, said shuttle comprising gripping means for receiving and gripping a detachable butt carrying a flanged pирн tube when said butt is forced with said pирн tube into the shuttle, guide means presenting sloping surfaces adapted to engage the flange of said pирн tube as it is entering the shuttle and to urge said flange into engagement with a face of said butt, and holding means adapted to engage said flange in the shuttle and to hold it firmly in engagement with said face when said butt is gripped by said gripping means.
- 10 2. A shuttle according to claim 1 wherein the guide means and the holding means are in the form of springs adapted to hold the flange in contact with the face of the detachable butt by spring pressure.
- 15 3. A shuttle according to claim 2 wherein the gripping means are in the form of two springs extending parallel to the length of the shuttle, and wherein the guiding and holding means are constituted by extensions of said springs reaching from the ends of said springs upwards, inwards, rearwards and downwards.
